METHOD OF MAKING HEAVY PARTS OF MACHINERY, AND THE RESULTING PRODUCTS

Frank C. Hasse, Chicago, Ill., assignor, by mesne assignments, to Union Carbide and Carbon Corporation, a corporation of New York

Application August 27, 1938, Serial No. 227,086

17 Claims. (Cl. 29—148)

This invention relates to heavy parts of machinery, such as locomotive cross heads and driving boxes and, more particularly, to heavy machinery parts which are flame-cut from a single forged or rolled steel billet; and to a method of making such heavy machinery parts.

It has been customary to form heavy machinery parts, such as locomotive crossheads and driving boxes, of cast steel, making the castings of substantially the finished shape and machining the surfaces of parts which are to be fitted. Such heavy machinery parts, however, are subject to the defects and uncertainties of castings, and the breaking of such parts is almost certain to result in property damage, and possibly even personal injury.

One object of the invention, therefore, is to provide heavy machinery parts which will have the properties of forged, rolled, or otherwise hot-worked members and which will not be subject to the weaknesses of castings or their liability to breakage. Another object is to provide a simple method whereby heavy machinery parts, such as crossheads and driving boxes, may be easily and economically cut from a steel billet, in order that billets instead of many different sizes of such heavy parts may be kept in stock in repair shops. These and other objects and the novel features will become apparent upon consideration of the present specification.

The invention is illustrated by way of example in the accompanying drawings, in which:

Fig. 1 is a side view of two crossheads, the steel billet from which they are cut being shown in broken line outline;

Fig. 2 is a plan view of the embodiment illustrated in Fig. 1;

Fig. 3 is a side view, similar to Fig. 1, of two crossheads of a different type;

Fig. 4 is a plan view of the embodiment illustrated in Fig. 3;

Fig. 5 is a side view of two locomotive driving boxes, the billet from which they are cut being shown in broken line outline;

Fig. 6 is a plan view of the two driving boxes illustrated in Fig. 5; and

Fig. 7 is an end view of the two driving boxes as seen from the right in Fig. 5.

I have found that heavy machinery parts may be easily cut from a solid unitary steel billet by means of a suitable flame-cutting machine, for instance, using an oxygen cutting blowpipe. Instead of a flame-cutting machine, a hand cutting blowpipe may be used. The billet may be supplied to the flame-cutting apparatus as re-

ceived from the rolling mill, or the forging of the billet may be performed in the same shop as the flame-cutting operation. I find it preferable to cut or shape a single billet to provide, in one operation, a blank of two identical heavy machinery parts in connected relation with a common boundary between them, and then to cut apart along the common boundary the parts so formed to produce two separate machinery parts which frequently are of substantially identical size and shape. The steel billet desirably is of substantially rectangular cross-section and has the rough form and outside dimensions of two of such parts arranged end-to-end. The billet is flame-cut along its six sides and between such sides to closely approximate the form and dimensions of the two substantially identical machinery parts in end-to-end and axially aligned connected relation. The parts are cut apart by flame-cutting the billet along a plane centrally between the parts and perpendicular to the common axis of the parts. The surfaces which require fitted contact with surfaces of cooperating members are machined, preferably before the severing operation which separates the parts, to facilitate the machining operation. Any desired number of parts, however, may be cut from a single billet by my method. Best results are obtained when the entire billet is first heated, that is to say, either taken hot from the rolls or the press which has forged it, or else raised from the cold state to the desired temperature for flame-cutting. It is possible, however, to cut the machinery part from a cold billet by using greater volumes of the heating and cutting gases.

In Figs. 1 and 2 of the drawings there is shown in broken line outline a steel billet B of substantially rectangular cross section from which a pair of alligator type crossheads C, C are cut to shape with a minimum waste of material. After the shaping operation has been completed, the two crossheads are still integrally connected by the stem elements 3, 3 to which piston rods are to be secured when the crossheads are assembled on a locomotive. Each element 3 is integral with a bifurcated body member 4 which has the usual shoes or gibbs secured thereto when the crosshead is in the guides of a reciprocating engine.

The crossheads are formed by flame-cutting the two crossheads in one operation from the single billet B, along the outlines indicated in full lines in the drawings, to provide two identically shaped parts in end to end and connected relationship. Subsequently, the two crossheads are cut apart by flame severing along the cen-

tral transverse line 5 perpendicular to the common axis of the crossheads to provide individual crossheads having contour portions at opposite faces in each dimension flame-cut to size. A 5 hole 6 is also flame-cut in each bifurcation of each body member 4 to receive the usual pivotal wrist pin connection for a connecting rod. Portions which require fitting, as the edge surfaces 7 of the bifurcations against which the shoes or 10 gibs are fitted, are subsequently machined; or, for convenience in handling, such portions may be machined prior to cutting apart the crossheads.

Thus, in cutting a pair of crossheads as illustrated in Figs. 1 and 2, from the billet shown in broken lines, the billet is placed with the face illustrated in Fig. 2 upward. The complete contour of the side and end surfaces of the two crossheads is then flame-cut from the billet, 15 the material between the broken line outline of the billet, as shown in Fig. 2, and the crossheads as outlined in full lines being cut away by the flame. During this operation the recess 8, adapted to receive the end of a connecting rod, is 20 cut between the side surfaces of the billet, thereby forming the bifurcations of each bifurcated body member 4. Following this, the billet is turned through 90 degrees bringing the face illustrated in Fig. 1 upward and the complete outline of the top, bottom, and ends of the two joined crossheads, as shown in full lines in Fig. 1, is 25 flame-cut at least to the depth of the upper bifurcations of the body members 4, and the holes 6, 6 are also cut in each of the upper bifurcations. 30 At this time, next, the workpiece or block is turned completely over, that is to say, through 180 degrees until its opposite side is up and the corresponding cuts are made on this side, including completion of the cut outlining the two 35 joined piston rod attachment elements 3, 3 and, of course, the holes 6, 6 arranged opposite and axially aligned with the holes 6, 6 in the upper bifurcations. The sections 9, 9, between each pair of bifurcations and the elements 3, 3, may 40 be cut out with a hand torch. The last cut of all is that along a perpendicular plane through the line 5, which severs the two crossheads.

In flame-cutting crossheads from solid steel billets in the manner which has been described, 50 it is preferable to use a heavy duty machine operated cutting blowpipe and appropriate patterns or templets, in conjunction with such an apparatus as that described in Patent No. 1,774,865, granted September 2, 1930, to Isaiah Allison for "Blowpipe apparatus."

As has been previously indicated, it is possible to cut the crossheads from a cold billet if sufficient volumes of heating and cutting gases are used; but it is preferable to cut them from a billet 60 which has been previously heated. It has been found that it is most economical and productive of the best physical properties in the resulting products to flame cut the billet while the same is heated to a temperature of at least 750 degrees Fahrenheit, and preferably one heated to between 750 and 850 degrees Fahrenheit. By thus preheating the entire billet prior to the flame-cutting or shaping operation, the resulting product will be substantially free from strains 65 and distortion throughout its mass.

After flame-cutting the outlines of the two crossheads and the holes 6, and, if desired, before separating them by cutting along the line 5, the holes 6 in the members 4 are internally machined, and the faces 7, 7 on the edges of the

bifurcations are machined for proper fitting with the bearing shoes which are fitted in contact therewith. It will be unnecessary, of course, to machine other faces of the crosshead which do not require fitting or fitted contact with the surfaces of members cooperating with said crosshead, hence such other faces may be flame-cut to finished dimensions without leaving excess stock along the cutting line for machining.

Figs. 3 and 4 illustrate another type of crosshead and how a pair of such crossheads may be cut from a single billet B' of rectangular cross section. The crossheads C', C' are flame-cut from the billet B' in a manner generally the same as the method employed for fabricating the crossheads C, C. The billet B', shown by broken lines, is placed on edge on suitable supports with the face illustrated in Fig. 4 upward. First, the outline of the side and end surfaces of two bifurcated crossheads, having their bifurcations disposed in integral end-to-end relation, is flame-cut in the two dimensions seen in Fig. 4, portions being cut to finished dimensions. The interior cut between the side surfaces is now started on the central transverse boundary line 12 and the interior contour 13 is cut completely, thus providing a recess in each of the connected crossheads for the reception of the end of a connecting rod, and forming the bifurcations. The billet is next turned through 90 degrees with the face illustrated in Fig. 3 and the starting cut 12 upward, and the outside top, bottom, and end outline of the two crossheads as seen in this view is cut. After this, the holes 14, 14 are flame-cut, 20 portions being cut to finished dimensions, following which the rectangular holes 15, 15 are cut, and then the outline 16 between crossheads. The faces 17, 17, including the edges of the bifurcations, the holes 14, 14, and the holes 15, 15 may be cut to allow enough metal for machining. 25 The billet is next turned through 180 degrees and the corresponding contours and openings are flame-cut in the opposite side. The last cuts made are those corresponding to the outline 16, which effect the final separation of the two crossheads. The sections marked 18, 18 and the piston rod bores 19, 19 may be cut with a hand torch either before or after the two crossheads 30 have been otherwise flame-cut and separated.

After flame-cutting the oppositely arranged 50 axially aligned wrist-pin holes 14, the surfaces 17, and the bores 19, these holes and surfaces may be machined, as are also the inset surfaces 20. The machining operations may be performed either before or after separation of the crossheads, as may be found convenient. However, to facilitate handling and simplify fabrication, it is advantageous to machine the crossheads while they are still in connected relation and before separating them.

Figs. 5, 6 and 7 illustrate the principles of the invention applied to the fabrication of a pair of unitary bifurcated locomotive driving boxes, showing how they may be cut from a single rolled steel billet 21 of substantially rectangular cross 65 section.

According to this invention, the driving boxes 22, 22 are flame-cut from the billet 21 and machined by substantially the same general procedure employed for producing the crossheads, 70 as already described. The billet 21 may be placed on suitable supports with the face illustrated in Fig. 5 upward. The outline of two bifurcated driving boxes, having their bifurcations in integral end-to-end relation, is then cut in the two 75

dimensions seen in Fig. 5, including shoe and wedge channel clearances 23, 23. Next, the interior contour 24 is cut complete, including prominences 25, 25 to provide ledges and arcuate sockets 26, 26 to receive crown brasses. Thereafter, the central transverse severing cuts 27 may be made. The core K, formed by cutting contour 24, desirably is removed upon completion of the cuts 27 but may be temporarily allowed 10 to remain in position to hold the two driving or journal boxes together after the severing cut. Such core may be subsequently utilized for other purposes.

With the core K retained as a connecting 15 means, the billet is then turned through 90 degrees with the face illustrated in Fig. 6 upward, and the outside outline of two driving boxes as seen in this view is flame-cut, including the spring saddle seat recesses 28, 28. The core K 20 formed by cutting contour 24, if retained in position, is next removed, permitting complete separation of the two journal boxes.

The remaining operations may be performed 25 upon the journal boxes individually, and if the core is removed prior to flame-cutting the recesses 28, 28 and other cuts shown in Fig. 6, such recesses and cuts may also be performed upon the journal boxes individually. With the face illustrated in Fig. 7 upward, the shoe and 30 wedge channels 29 are flame-cut in each journal box, following which the box is placed with the face illustrated in Fig. 6 upward and the bottom contour 30 is cut thereon. After turning the box through 180 degrees, the cut corresponding 35 to contour 30 is made on the opposite side.

Contours 28, 30 and 31 at the top and bottom of the driving box may be flame-cut to finished dimensions or sufficient stock may be allowed for machining. In general, all surfaces which 40 require fitted contact with surfaces of cooperating members should be flame-cut to leave sufficient excess stock on the flame-cut surface for subsequent machining, and those which are not subject to such contact may be flame-cut to finished 45 dimensions. Thus, sufficient metal should be allowed when flame-cutting the contour 24, including ledges 25 and brass-receiving sockets 26, so that these surfaces may be machined subsequently. Also, during the machining operations, spring saddle seats 32 may be milled, or 50 drilled and chipped out of the top of the driving box. Oil cavities 33 may be subsequently drilled in the driving box, and also ducts 34 connecting the oil cavities with the innermost faces 55 of the shoe and wedge channels 29.

It will be evident that heavy machinery parts, such as crossheads and driving boxes, fabricated as described above, will have surfaces flame-cut to size and machined flame-cut surfaces, will 60 have a strong and tough structure substantially throughout their masses characteristic of forged or rolled steel, and will not be subject to the weaknesses of steel castings. The invention makes possible a reduced inventory expense and 65 other economies in railroad repair shops, since a relatively small stock of rolled steel billets is required as compared to a relatively large stock of assorted finished steel castings. Economies in 70 labor and gas consumption are also afforded by flame-cutting two or more machinery parts from a single billet during the same operation and setting. Furthermore, worn portions of a machinery part made of billet metal may be readily 75 built up by the oxy-acetylene process, and thus

the service life of a machinery part embodying this invention may be extended indefinitely.

The particular examples here illustrated and described are presented merely to indicate how the invention may be applied. It will be evident that certain features of the invention may be utilized independently of others; and various modifications, which do not depart from the principles of the invention, will be apparent to those skilled in this art.

This application contains subject matter in common with my copending application Serial No. 16,559, filed April 16, 1935.

I claim:

1. In a method of forming heavy parts of machinery, the steps which comprise providing a single steel billet having the rough form and outside dimensions of a plurality of such parts in connected relation and arranged to have common boundaries between adjacent parts; flame-cutting said billet to the desired contours of a plurality of such connected parts; and separating the machinery parts so formed by flame-cutting along the common boundaries.

2. In a method of forming heavy parts of machinery, the steps which comprise providing a single steel billet having the rough form and outside dimensions of a plurality of such parts in connected relation and arranged to have common boundaries between adjacent parts; flame-cutting said billet to the desired contours of a plurality of such connected parts, but leaving sufficient excess stock for machining on those surfaces of said parts which require fitted contact with surfaces of cooperating members; machining said parts to remove such excess stock; and separating the machinery parts so formed by flame-cutting along the common boundaries.

3. A method of forming a plurality of substantially identical parts of machinery such as locomotive crossheads and driving boxes, which comprises forging a single steel billet to the rough outside dimensions of at least two of such parts in end-to-end and axially aligned relation; flame-cutting portions of said billet to form said substantially identical parts in connected relation; machining surfaces of such connected parts which require fitting with surfaces of cooperating members; and separating the connected parts so formed and machined by flame-cutting perpendicularly to the common axis of and between such connected parts.

4. A method of forming two substantially identical heavy parts of machinery comprising providing a single steel billet having the rough outside dimensions of two such parts arranged end-to-end; flame-cutting the billet to the dimensions and form of two such parts in end-to-end and connected relation; and separating the connected machinery parts so formed by cutting along a plane centrally between said parts and perpendicular to the common axis of said parts to produce two separate machinery parts of substantially identical size and shape.

5. A method of forming heavy parts of machinery, which comprises providing a solid steel billet of substantially rectangular cross section and having the rough outside dimensions of two of such parts arranged end-to-end; flame-cutting said billet along its six sides and between such sides to the dimensions and form of two substantially identical machinery parts in end-to-end relation; and severing said parts by flame-cutting along a plane centrally between said parts and perpendicular to the common longitu-

dinal axis of said parts, to produce two separate machinery parts of substantially identical size and shape.

6. A method of forming heavy parts of machinery as claimed in claim 5, including the step of machining the surfaces of said parts which require fitted contact with surfaces of cooperating members, such machining being performed while said parts are still in connected relation and before performing the severing operation to separate them.

7. A method of forming heavy bifurcated parts of machinery, which comprises providing a single steel billet having the rough form and outside dimensions of two substantially identical bifurcated machinery parts having their bifurcations integrally joined in end-to-end relation; flame-cutting said billet to the desired exterior contour of such joined parts; flame-cutting said billet to the interior contour of said joined parts to form said integrally joined bifurcations; and severing said parts so formed by flame-cutting along the plane of joinder of said bifurcations and perpendicular to the common axis of said parts.

8. A method of forming heavy bifurcated parts of machinery which comprises providing a single steel billet having a substantially rectangular cross section and the rough form and outside dimensions of two substantially identical bifurcated machinery parts having their bifurcations integrally joined in end-to-end and opposed relation; shaping said billet to the exterior contour of said joined parts in two dimensions by flame-cutting; flame-cutting said billet to the interior contour of said joined parts in the aforesaid two dimensions to form the integral bifurcations and a core therebetween; severing the machinery parts so formed by flame-cutting along a central plane between said parts and perpendicular to their common axis; and flame-cutting the contour of said parts in the third dimension while maintaining said core in position to hold such severed parts together.

9. A method of forming crossheads comprising providing a steel billet having the rough outside dimensions of two crossheads arranged end-to-end; flame-cutting said billet to the dimensions and form of two crossheads in end-to-end and connected relation; and cutting apart the two crossheads so formed.

10. A method of forming crossheads comprising providing a steel billet having the rough outside dimensions of two crossheads; flame-cutting the two crossheads together from such billet; machining the surfaces of said crossheads which require fitting; and flame-cutting such formed crossheads apart.

11. A method of forming unitary steel crossheads comprising providing a solid steel billet of substantially rectangular cross section having the rough outside dimensions of two identical crossheads arranged end-to-end; heating said billet to between 750 and 850 degrees Fahrenheit; flame-cutting such heated billet to the desired substantially finished contours of two identical crossheads in end-to-end and connected relation; and flame-cutting said crossheads apart to produce two separate identical crossheads.

12. A method of forming crossheads comprising forging a billet to the rough outside dimensions of two crossheads; heating the said billet to between 750 and 850 degrees Fahrenheit; flame-cutting such heated billet to the desired contours of two connected crossheads; machining

the surfaces of said crossheads which require fitting; and cutting apart said two crossheads.

13. In a method of forming unitary steel crossheads, the steps which comprise providing a steel billet of substantially rectangular cross-section and having the rough outside dimensions of two crossheads arranged in end-to-end and connected relation; flame-cutting portions of two opposite faces of said billet to finished dimensions to form side surfaces of said connected crossheads; flame-cutting portions of the two end surfaces of said billet to finished dimensions to form end surfaces of said connected crossheads; flame-cutting said billet between such side surfaces to provide a recess in each of said connected crossheads adapted to receive the end of a connecting rod, thereby forming bifurcations on each of said connected crossheads; flame-cutting two opposite surfaces of said billet to form the top and bottom surfaces of said connected crossheads, but leaving sufficient metal on portions thereof for machining to fit bearing shoes; flame-cutting oppositely arranged axially aligned holes in the bifurcations of each crosshead to receive wrist-pins, but leaving sufficient metal for machining; machining said holes; machining portions of the top and bottom surfaces of said crossheads, including the edges of said bifurcations, to fit with bearing shoes; and flame-cutting said crossheads apart.

14. A unitary steel crosshead made from a solid steel billet of substantially rectangular cross-section, said crosshead comprising bifurcations and having contour portions at opposite faces thereof in each dimension flame-cut to size, said crosshead having oppositely arranged axially aligned holes in said bifurcations adapted to receive a wrist pin, the walls of such holes comprising machined flame-cut surfaces, and said crosshead having contour portions on the top and bottom surfaces thereof, including the edges of said bifurcations, comprising machined flame-cut surfaces adapted to engage and fit closely with bearing shoes.

15. A unitary crosshead blank made from a solid steel billet of substantially rectangular cross-section, said crosshead blank comprising two connected crossheads having a common boundary therebetween, each of said connected crossheads comprising bifurcations and having contour portions at opposite faces thereof flame-cut to size, each of said connected crossheads having oppositely arranged axially aligned holes in said bifurcations adapted to receive wrist pins, the walls of such holes comprising machined flame-cut surfaces, and each of said connected crossheads having contour portions on the top and bottom surfaces thereof, including the edges of said bifurcations, comprising machined flame-cut surfaces adapted to engage and fit closely with bearing shoes.

16. A method of forming steel driving boxes comprising providing a single steel billet having the rough outside dimensions of two driving boxes arranged end-to-end; flame-cutting said billet to the dimensions and form of two driving boxes in end-to-end and connected relation; and cutting apart the driving boxes so formed.

17. A method as set forth in claim 16, wherein said billet is heated to a temperature above about 750° F. prior to said flame-cutting operation, and the surfaces of said driving boxes which require fitting are machined after such flame-cutting operation.
